DESIGN FOR A CIGARETTE DISPENSER

Jacob E. Gould, Detroit, Mich., assignor to Detroit Macoid Corporation, Detroit, Mich., a corporation of Michigan

Application June 6, 1938, Serial No. 77,624

Term of patent 7 years

To all whom it may concern:

Be it known that I, Jacob E. Gould, a citizen of the United States, residing at Detroit, Wayne County, Michigan, have invented a new, original, and ornamental Design for a Cigarette Dispenser, of which the following is a specification, reference being had therein to the accompanying drawing forming a part thereof, in which:

Fig. 1 is a top plan view of the cigarette dispenser showing my new design;

Fig. 2 is a side elevation thereof; and

Fig. 3 is a bottom plan view of the cigarette dispenser.

The design is characterized by a body of the configuration shown, and a cover member provided with a centrally disposed pivot having an upwardly extending finger hold, all disposed and combined in the particular relationship shown.

I claim:

The ornamental design for a cigarette dispenser, substantially as shown and described.

JACOB E. GOULD.
